US0D1016439S

(12) **United States Design Patent** (10) **Patent No.:** **US D1,016,439 S**
(45) **Date of Patent:** **** Mar. 5, 2024**

(54) **FOOTWEAR ARTICLE**

(71) Applicant: **SALOMON S.A.S.**, Epagny Metz-Tessy (FR)

(72) Inventor: **Baptiste Tarenne**, Pringy (FR)

(73) Assignee: **Salomon S.A.S.**, Epagny Metz-Tessy (FR)

(**) Term: **15 Years**

(21) Appl. No.: **29/784,338**

(22) Filed: **May 19, 2021**

(30) **Foreign Application Priority Data**

Dec. 15, 2020 (WO) WIPO100285

(51) **LOC (14) Cl.** **02-04**

(52) **U.S. Cl.**

USPC **D2/908**; D2/902; D2/907

(58) **Field of Classification Search**

USPC D2/902-908, 909, 947, 951, 959, 969
CPC .. A43B 1/009; A43B 1/02; A43B 1/04; A43B

(57) **CLAIM**

I claim the ornamental design for a footwear article, as shown and described.

DESCRIPTION

FIG. 1 is an image of a first side view of a footwear article; FIG. 2 is an image of a second side view of the footwear article of FIG. 1;

FIG. 3 is an image of a first side, front perspective view of the footwear article of FIG. 1;

FIG. 4 is an image of a front view of the footwear article of FIG. 1

FIG. 5 is an image of a rear view of the footwear article of FIG. 1;

FIG. 6 is an image of a top view of the footwear article of FIG. 1; and,

FIG. 7 is an image of a bottom view of the footwear article of FIG. 1.

1 Claim, 5 Drawing Sheets
